UNITED STATES PATENT OFFICE.

JOHN B. TAYLOR, OF SCHENECTADY, NEW YORK, ASSIGNOR TO GENERAL ELECTRIC COMPANY, A CORPORATION OF NEW YORK.

SYSTEM OF DISTRIBUTION.

No. 873,107.

Specification of Letters Patent.

Patented Dec. 10, 1907.

Application filed January 4, 1906. Serial No. 294,566.

To all whom it may concern:

Be it known that I, JOHN B. TAYLOR, a citizen of the United States, residing at Schenectady, county of Schenectady, State of New York, have invented certain new and useful Improvements in Systems of Distribution, of which the following is a specification.

My invention relates to alternating-current distribution, and particularly to railways operated by alternating-current. If a low-voltage conductor, such as a telegraph or telephone wire, extends in close proximity to a conductor carrying single-phase alternating-current, the low-voltage conductor is subject to disturbances due to induction both static and magnetic. Thus, in a single-phase alternating-current railway a telegraph wire on the same poles with the working conductor is subject to such disturbances. The disturbances due to magnetic induction are largely avoided when sub-stations are connected to both ends of the working conductor. For instance, if a section of the working conductor extending between two sub-stations is considered, it will be seen that with a car in the middle of the section, the current in one-half the section will neutralize the inductive effect of the current in the other half, and when the car is not in the center the tendency to neutralization continues, since when the car is nearer one end of the section than the other, the shorter part of the section carries a greater current.

My invention consists in arranging such a system with the working conductor sectioned at the sub-stations and connected so that static induction is avoided. I accomplish this by so connecting the transformers at the sub-stations that adjacent sections are maintained at relatively opposite potentials with respect to earth. That is, when one section is positive with respect to earth the adjacent section at the same instant will be negative with respect to earth. Consequently, the static inductions of the two sections on an adjacent conductor will neutralize each other.

My invention further consists in supplying potentials as above described to both ends of each section. In this manner magnetic inductive effects of both kinds are also avoided, for the reasons already explained.

My invention will best be understood by

reference to the accompanying drawings, in which

Figure 1 shows diagrammatically the distribution system of a single-phase railway; and Fig. 2 shows a modification of the arrangement of transformers at a sub-station.

In Fig. 1, H represents the high-tension conductors from which energy is supplied to the working conductor through sub-stations comprising step-down transformers. Such transformers are indicated at T¹, T² and T³. The working conductor is formed in sections S¹, S², S³ and S⁴, each section extending from one sub-station to another. The central point of the secondary of each sub-station transformer is connected to earth and the outer terminals of the secondary winding are connected to the ends of the two sections ending at that sub-station. With this arrangement it will be seen that at the instant when one section, as, for instance, S² is at a positive potential with respect to earth the adjacent section S³ will be at an equal negative potential. Consequently if a low-voltage conductor C extends parallel with and adjacent to the working conductor, the static inductions of the two sections S² and S³ on the conductor C will neutralize each other. Since, as has been explained heretofore, the currents in the two portions of each section of the working conductor supplying a car neutralize each other, as far as magnetic induction upon the adjacent conductor C is concerned, practically all inductive effects upon the conductor C are avoided.

Many other arrangements of the transformers supplying the working conductor may be employed. Thus, for instance, in Fig. 2 I have shown two separate transformers t and t', each supplying one end of one section. For this purpose one terminal of the secondary winding of each transformer is earthed and the other connected to the end of the section supplied.

I do not desire to limit myself to the particular construction and arrangement of parts here shown, but aim in the appended claims to cover all modifications which are within the scope of my invention.

What I claim as new, and desire to secure by Letters Patent of the United States, is,—

1. In a system of distribution, a conductor comprising a plurality of insulated sections,

and sources of alternating voltage connected between each section and earth and arranged to supply to a portion of said sections a positive potential with respect to earth at the instant the remaining sections are at a negative potential with respect to earth.

2. In a system of distribution, a conductor comprising a plurality of insulated sections, and sources of alternating voltage connected between each end of each section and earth and arranged to supply to a portion of said sections a positive potential with respect to earth at the instant the remaining sections are at a negative potential with respect to earth.

3. In a system of distribution, a conductor comprising a plurality of insulated sections, and sources of alternating voltage connected between each end of each section and earth and arranged to supply to adjacent sections relatively opposite potentials with respect to earth.

4. In a railway system operated by alternating-current, a plurality of sub-stations, a working conductor composed of sections each extending between adjacent sub-stations, and transformers at said sub-stations connected between the ends of each section and earth, said transformers being arranged to supply to a portion of said sections a positive potential with respect to earth at the instant the remaining sections are at a negative potential.

5. In a railway system operated by alternating-current, a plurality of sub-stations, a working conductor composed of sections each extending between adjacent sub-stations, and transformers at said sub-stations connected between the ends of each section and earth and arranged to supply to adjacent sections relatively opposite potentials with respect to earth.

6. In a system of distribution, a conductor comprising a plurality of insulated sections, a supply circuit, and transformers having their primaries connected in multiple to the supply circuit and their secondaries connected between the sections of said con-

ductor and earth and arranged to maintain a portion of said sections at a potential opposite with respect to earth to the potential of the other sections.

7. In a system of distribution, a conductor comprising a plurality of insulated sections, a supply circuit, and transformers having their primaries connected in multiple to the supply circuit and their secondaries connected between the sections of said conductor and earth and arranged to supply current to both ends of each section and to maintain a portion of said sections at a potential opposite with respect to earth to the potential of the other sections.

8. In a railway system operated by alternating-current, a plurality of sub-stations, a working conductor composed of sections each extending between adjacent sub-stations, a supply circuit extending through the sub-stations, and transformers at said stations having their primaries connected in multiple to said supply circuit and their secondaries connected between the sections of said conductor and earth and arranged to maintain a portion of said sections at a potential opposite with respect to earth to the potential of the other sections.

9. In a railway system operated by alternating-current, a plurality of sub-stations, a working conductor composed of sections each extending between adjacent sub-stations, a supply circuit extending through said sub-stations, and transformers at said sub-stations having their primaries connected in multiple to the supply circuit and their secondaries connected between the sections of said conductor and earth and arranged to supply current to both ends of each section and to maintain a portion of said sections at a potential opposite with respect to earth to the potential of the other sections.

In witness whereof, I have hereunto set my hand this 3rd day of January 1906.

JOHN B. TAYLOR.
